Des. 68

John B. Blute Schenectady, N.Y.
Letters Patent, Design No. 68, dated 23rd July 1846

The Schedule referred to in these Letters Patent and making part of the same.

To all whom it may concern:

Be it known, that I, John B. Blute of Schenectady in the County of Schenectady and State of New York, have invented or produced a new design for an ornamental Vase, and I do hereby declare, that the accompanying drawing is a full and correct representation thereof.

The neck of my vase is encircled by six female figures in a sitting posture, with joined hands - Immediately beneath those figures are heads of lions alternating with fruits &c. The handles are after the grotesque manner, consisting of female figures, the extremities of which, run into scrolls & foliage.

connected with the vase at the top by two sitting male figures. - The body of the vase exhibits upon two sides a medallion female bust supported by a Grotesque head, and surrounded with scrolls &c. under each handle is a grotesque head with lolling tongue.

The foot of the vase is ornamented with grotesque heads, fruits, foliage &c. The whole although not easily described in words being fully represented in the drawings. Both sides exhibit equally the same ornamental figures. My vase was designed especially with reference to its being cast in metal, but may of course be executed in any other suitable material.

What I claim as my invention and desire to secure by letters Patent is the combination and arrangement of one ornamental figures and forms, exhibited in the accompanying drawings, forming a design for an Ornamental Vase.
